US00D997563S

(12) **United States Design Patent** (10) **Patent No.:** **US D997,563 S**
(45) **Date of Patent:** **** Sep. 5, 2023**

(54) **DUFFEL BAG**(71) Applicant: **YETI Coolers, LLC**, Austin, TX (US)(72) Inventors: **Roy Joseph Seiders**, Austin, TX (US); **Erik Steven Larson**, Austin, TX (US); **Derek G. Sullivan**, Austin, TX (US); **Alex Baires**, Austin, TX (US); **Jeffrey Charles Munie**, Austin, TX (US)(73) Assignee: **YETI Coolers, LLC**, Austin, TX (US)(***) Term: **15 Years**(21) Appl. No.: **29/846,959**(22) Filed: **Jul. 20, 2022****Related U.S. Application Data**

(63) Continuation of application No. 29/747,996, filed on Aug. 26, 2020, now Pat. No. Des. 958,530, which is a continuation of application No. 29/695,010, filed on Jun. 14, 2019, now Pat. No. Des. 897,102, which is a continuation of application No. 29/634,458, filed on Jan. 22, 2018, now Pat. No. Des. 853,115.

(74) *Attorney, Agent, or Firm* — Banner & Witcoff, Ltd.

(57) **CLAIM**

The ornamental design for a duffel bag, as shown and described.

DESCRIPTION

FIG. 1 is a top, front, right perspective view of a duffel bag showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate portions of the duffel bag and form no part of the claimed design.

1 Claim, 6 Drawing Sheets
